DRAG SCRAPER

Robert G. Le Tourneau, Peoria, Ill., assignor to
R. G. Le Tourneau, Inc., Stockton, Calif., a cor-
poration of California

Application August 10, 1936, Serial No. 95,148

6 Claims. (Cl. 37—169)

This invention relates to wheel and tractor supported drag scrapers; my principal objects being to provide a scraper of this character in which the wheels and bowl are so mounted relative to each other and controlled so that a great range of vertical movement of the bowl may be had; one in which the bowl may be disposed at a transverse tilt relative to the wheels so as to make the scraper suitable for sidehill work; and one having an efficient and easily operated means to hold the bowl in a raised position for transportation, without relying on the tension of the control cable or other operating mechanism.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation of the scraper in a scraping position.

Figure 2 is a sectional elevation of the scraper in a raised transporting position.

Figure 3 is a fragmentary plan section taken on the line 3—3 of Fig. 1.

Referring now more particularly to the characters of reference on the drawing, the bowl of the scraper comprises side plates 1 and a back plate 2, the lower portion of which is disposed with a forward slope to its lower end and has a scraping plate 3 across such end and set at the same slope. This slope is such that while the weight of the dirt in the bowl when the latter is in a scraping position tends to hold the same down so as to enable the plate to properly dig into the ground and avoid chattering, while at the same time such dirt will readily slide off the plate when the bowl is lifted the relatively short distance necessary for leveling purposes. This slope is substantially 45° to the horizontal.

A cross beam 4 connects the side plates at the top and front, and a rigid braced tongue 5 extends forwardly and downwardly from said beam centrally thereof. At its forward end the tongue is provided with a swivel coupling unit 6 adapted for supporting connection with the draw bar 7 of the tractor.

Pivoted on the side plates at the front and substantially midway of their height are rigid arms 8. These extend to terminations rearwardly of the bowl and are rigidly connected behind the

same by a cross beam 9, so that said beam and arms form a substantially non-distortable unit. Standards 10 are rigid with and depend from this beam in transversely spaced relationship; these standards supporting wheels 11 which are disposed outwardly thereof.

One arm 8 is mounted on the adjacent side plate by a non-adjustable pivot 12. The pivot point of the opposite arm however is made vertically adjustable by the following means: the forward end of said arm projects between the adjacent plate 1 and a bracket plate 13 rigid with said side plate, and having a block 14 projecting from its outer face for its full height. The block and bracket plate as well as the plate 1 are provided with a number of vertically spaced sets of holes 15 and the such are adapted to receive the pivot pin 16 of the adjacent arm 8. This pin is of course removable and to prevent it from undesired removal, I provide a removable locking pin 17 which extends horizontally through the block 14 of the pin 16 as shown in Fig. 3. It is of course to be understood that the block is drilled at each pivot pin hole to receive the locking pin. In this manner by changing the position of the pivot bolt 16, and since the arms 8 and the wheels form a rigid unit, the bowl will be set at different transverse slopes as operating conditions may require.

The vertical movement of the bowl is controlled by a single tractor-operated cable 18 as follows: secured on end behind the bowl adjacent the bottom and centrally of its width is a sheave block 19, while occupying a similar position on the cross beam 9 and overhanging the block 19 is another sheave block 20. The cable 18 passes along and over the bowl from the tractor, about a direction changing pulley 21 fixed on the top of the bowl centrally thereof, down to the sheave block 19 and then up to the sheave block 20; passing about and between these sheaves to an anchor as at 22 on the latter. It will thus be seen that by pulling on the cable the bowl will be raised relative to the wheels, while lowering of the bowl is effected by slackening up on the cable and allowing the weight of the bowl to cause it to drop. Due to the length of the arms 8 a relatively large raising and lowering movement of the bowl may be easily had (about three feet at the back being obtainable) which is sufficient for deep scraping as well as providing for a high ground clearance of the bowl when being transported. At the same time the wheel mounting arms 8 do not relatively move through any excessively great arc.

When it is desired to transport the scraper 1

have provided a means to enable the bowl to be held in the necessary raised position without having to maintain the cable 18 on a tension. This means comprises a link 23 pivoted on and depending from the underside of the beam 9 and lugs 24 mounted on and projecting rearwardly from under the sheave block 19. The lugs and the lower end of the link are drilled to receive a coupling pin 25. Therefore when the bowl has been raised by a pull on the cable sufficient so that the hole in the link when swung between the lugs alines with those in the lugs, the pin 25 may be projected thereto and the tension on the cable may then be released. The weight of the bowl will then be entirely supported by the link and since the bowl is then of course empty and the link is on a tension besides being in a central position relative to the width of the bowl, said link will easily support its load without undue strain.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A drag scraper comprising a bowl having side plates, means to support the bowl at the front from the ground, arms pivoted on the side plates adjacent their forward ends and projecting beyond the rear end of the bowl, a cross beam rigidly connecting said arms rearwardly of the bowl, ground engaging wheels mounted in connection with said cross beam, and means between the cross beam and the bowl below the beam to control the raising and lowering of the bowl.

2. A drag scraper comprising a bowl, means to support the bowl at the front end from the ground, arms pivoted on the bowl adjacent its forward end and projecting beyond the rear end of the bowl, wheels mounted in connection with the arms, a crossbeam connecting the arms rearwardly of the bowl, means to raise and lower the bowl, a link mounted on and depending from the cross beam, lugs mounted on and projecting rearwardly from the bowl in alinement with the

link, said lugs and link having holes adapted to match when the bowl is raised a predetermined distance and a coupling pin adapted for removable placement through the holes.

3. A drag scraper comprising a bowl having side plates, means to support the bowl at the front from the ground, arms pivoted on the side plates adjacent their forward ends and projecting beyond the rear end of the bowl, a cross beam rigidly connecting said arms rearwardly of the bowl, ground engaging wheels mounted in connection with said cross beam, a sheave mounted on the bowl behind and toward the bottom thereof centrally of its width, another sheave mounted on the cross beam in alinement with the bowl sheave, a direction changing pulley on the back of the bowl at the top, and a pull cable extending over the pulley from in front, down to and over the bowl sheave and up to and over the cross beam sheave to an anchor adjacent one of said sheaves.

4. A drag scraper comprising a bowl having side plates, a tongue rigid with and projecting forwardly from the bowl and adapted at its front end for swivel connection with a tractor, arms extending along the side plates outwardly of the bowl to a termination rearwardly of the same, a member rigidly connecting the arms at their rear ends, wheels supporting said member from the ground, pivot connections between the arms and bowl, and means to adjust the pivot connection of one arm vertically.

5. A structure as in claim 4 in which said last named means comprises a bracket plate mounted on the adjacent side plate of the bowl and overlapping the front end of the adjacent arm, a block rigid with and projecting outwardly from the bracket plate, said block, bracket plate and side plate having vertically spaced sets of matching holes, a pin for removable placement through the arm and any set of holes, and a cross pin for removable placement through the block and pin.

6. A drag scraper comprising a bowl, means to support the bowl at the front end from the ground, arms pivoted on the bowl adjacent its forward end and projecting beyond the rear end of the bowl, wheels mounted in connection with the arms, a cross beam connecting the arms rearwardly of the bowl, tension means connecting the cross beam and bowl below said beam, and control means to alter the effective length of said tension means.

ROBERT G. LE TOURNEAU.
